UNITED STATES PATENT OFFICE.

THOMAS A. DELANEY, OF CHICAGO, ILLINOIS, ASSIGNOR TO HILLS-McCANNA COMPANY, OF CHICAGO, ILLINOIS.

LUBRICATOR.

SPECIFICATION forming part of Letters Patent No. 749,477, dated January 12, 1904.

Application filed April 24, 1902. Serial No. 104,474. (No model.)

To all whom it may concern:

Be it known that I, THOMAS A. DELANEY, of Chicago, Illinois, have invented certain new and useful Improvements in Lubricators, 5 whereof the following is a specification.

This invention relates more particularly to the class of lubricators in which the lubricant is drawn from a reservoir and forced to the point of application by a pump.

10 In feeding materials of non-homogeneous composition—as, for example, soapsuds, oils containing sediment, graphite lubricants, &c.—it has been found that the heavier matters have a tendency to separate from the body 15 of the material and not only not be fed properly, but clog or affect the valves of the lubricator, so that it failed to work right. My present invention is intended to obviate these objections.

20 To this end it consists in certain devices or combinations which are pointed out in the claims at the end hereof.

In the drawings, Figure 1 is a front elevation of a lubricator containing my invention with 25 a portion of the front wall of the reservoir broken away to show the interior thereof. Fig. 2 is a plan view of the same with the top of the reservoir partly broken away to show the interior.

30 In the figures, 1 is the reservoir. 2 is a pump mounted on the reservoir and provided with suction 3 and discharge 4. 5 is a cross-head moving on the guide-studs 6 and reciprocated by the motor 7 in the usual manner. The 35 pump-rod 8 passes through an ear 9 on the cross-head and is provided with adjusting-nuts 10, so that the pump is operated by the reciprocation of the cross-head. All these 40 parts are fully described in the patent granted to McCanna and myself October 2, 1900, No. 659,166.

45 11 represents rods, screw-threaded on their upper ends, as shown, and passing through ears 12 on the cross-head 5 and connected therewith by nuts 13 on each side of the ears. These rods extend downward through stuffing-boxes 14 into the reservoir. At the lower ends of these rods, and preferably near the bottom of the reservoir, is a plate 15, suitably 50 attached to the rods, so as to reciprocate with them when they are moved by the cross-head. This plate is perforated as shown at 16, to per-

mit the passage of the pump-suction, and it is enough smaller than the reservoir to move easily therein and churn the contents as it 55 moves and keep them stirred up.

While my invention, as above set forth, is intended more particularly for lubricating purposes, it is sometimes available for other and analogous uses. For example, I have used 60 it for feeding boiler compound to boilers and have had great success with it for that use.

I claim—

1. In combination with the reservoir, a suction-pipe extending into the reservoir, a pump 65 for drawing through the pipe and a reciprocating stirrer within the reservoir and connected with a moving member of the pump to be reciprocated therefrom, substantially as described.

2. The combination with the reservoir, of a pump drawing from the reservoir and having a cross-head through which the pump is rendered active, and a stirrer located in the reservoir and connected with the cross-head to be 75 actuated therefrom, substantially as described.

3. The combination with the reservoir, of a pump having its suction extending from the top toward the bottom of the reservoir and its discharge above the suction, of a stirrer in the 80 reservoir and connected with a moving member of the pump to be actuated therefrom, substantially as described.

4. In combination with the reservoir, and the pump mounted thereon, and the cross-head 85 by which the pump is operated, rods extending from the cross-head into the reservoir, and a plate connected to said rods and fitting loosely in the reservoir, whereby the contents of the reservoir are churned or stirred up when the 90 pump is in operation, substantially as and for the purpose set forth.

5. In combination with the reservoir, the pump and the cross-head by which the pump is operated, rods adjustably connected to said 95 cross-head, and extending into the reservoir and a plate connected to said rods and fitting loosely in the reservoir, the pump-suction inlet being below said plate, substantially as and for the purpose set forth.

THOMAS A. DELANEY.
